UNITED STATES PATENT OFFICE.

WILLIAM O. HORN, OF NEW YORK, N. Y.

DESIGN FOR A NECKSCARF.

SPECIFICATION forming part of Design No. 32,240, dated February 13, 1900.

Application filed December 19, 1899. Serial No. 740,944. Term of patent 3 $\frac{1}{2}$ years.

To all whom it may concern:

Be it known that I, WILLIAM O. HORN, a citizen of the United States, residing in the city, county, and State of New York, have invented and produced a new and original Design for a Neckscarf, of which the following is a specification, reference being had to the accompanying drawing, forming part thereof.

The leading feature of my design for a neckscarf is a body of the form of a standing collar, an upward deflection of the lower edge of said collar, narrow tie portions extending from the ends of said collar, and wide tie portions extending from said narrow portions.

The figure represents a front view of a neckscarf embodying my design.

In the drawing, A designates a neckscarf,

the same consisting of the body B of the form of a standing collar, the upward deflection C of the lower edge thereof, the narrow tie portions D D, and the wide tie portions E E. In said collar, near the under edge thereof, are the buttonholes F and G, the holes G being in series at the front of the collar and the hole F being single at the rear of the collar. 20

Having thus described my invention, what I claim as new, and desire to secure by Letters Patent, is—

The design for a neckscarf substantially as shown and described.

WILLIAM O. HORN.
